UNITED STATES PATENT OFFICE.

JOHN F. ROBB, OF CLEVELAND HEIGHTS, OHIO, ASSIGNOR, BY MESNE ASSIGNMENTS, TO KOEHRING COMPANY, OF MILWAUKEE, WISCONSIN, A CORPORATION OF WISCONSIN.

MACHINE FOR LAYING REINFORCED CONCRETE ROADS.

Application filed March 26, 1921. Serial No. 455,886.

To all whom it may concern:

Be it known that I, JOHN F. ROBB, a citizen of the United States, residing at 3111 Yorkshire Road, Cleveland Heights, in the county of Cuyahoga and State of Ohio, have invented certain new and useful Improvements in Machines for Laying Reinforced Concrete Roads, of which the following is a specification.

From the viewpoint of advanced engineering, the development of concrete road construction today points to the necessity of employing metal reenforcement for such roads for obviating as much as possible the liability of longitudinal cracking or breaking. This cracking or breaking of the concrete road is due of course to different causes, but it has been found that the liability of the cracking is much reduced when metal reinforcing is utilized, somewhat after the manner of the use of this material in concrete construction generally.

The purpose in view in the development of the present invention has been to devise a machine and method for facilitating the laying of concrete roads in two sections, a base section and surface section, with the reinforcing properly disposed between said sections. The common method in use today for doing the above work has been to lay the base or bed section of concrete upon the subgrade, by a suitable distributing machine, then dispose upon said base section suitably cut sections of the reinforcing metal. The second step just referred to is attended to by hand and involves expensive manual labor, at the same time delaying the general operation of constructing the road because the mixing and distributing machine usually employed cannot progress until after it has laid the surface layer or section of concrete upon the base layer or section, and upon the previously deposited reinforcing.

The machine or method proposed by me permits of applying the reinforcing material to the base section of concrete first laid by mechanical devices, and in a continuous manner as the machine progresses. Furthermore, the invention involves the laying of the surface section of concrete simultaneously with the laying of the reinforcement in

position upon the base section. The invention involves additionally the method of simultaneously laying the surface section of concrete and the reenforcement in a continuous and progressive manner as the distributing machine by which the surface section aforesaid is deposited steadily progresses in the road laying operation.

The invention involves additionally the utilization of a derrick type loading means for the distributing and mixing unit employed, to carry the aggregates thereto, said derrick means being additionally available for lifting bales, or similar supplies of reinforcing material into place upon the machine ready to be fed therefrom as the machine progresses.

In the accompanying drawings:—

Figure 1 is a side view of distributing machines for mixing concrete, distributing the concrete in two layers, and feeding the reinforcing to the road bed for deposit upon the base section of concrete first laid.

In the drawings A denotes the subgrade on which the road is to be constructed, B the base layer or section of concrete adapted to be deposited upon the subgrade by a distributing machine 2 constructed largely in accordance with the type of machine illustrated in United States Letters Patent of Lichtenberg No. 1,141,470, issued June 1, 1915. The machine 2 has a distributing bucket 5 adapted to travel on a boom 4 and a suitable mixer may be provided for said machine, same being partially illustrated at 3. I show at C a surface layer of concrete as when being deposited upon the base layer B; also there is illustrated at D the reinforcing material in the act of being laid upon the base section B of concrete.

To lay the surface section C of the concrete and the reinforcing D, I have devised a special machine designated 8 and consisting of suitable framework having the supporting wheels 9 arranged to travel upon the road forms E which act as rails for the support of the machine 8. At one end the machine 8 is equipped with a carrier or suitable supporting means 10^a for a bale 10 of reinforcing material. The bale 10 is supported by a removable shaft 10^b which is used in connection with a grapple on the

derrick device hereafter described, to facilitate placing fresh bales of reenforcing in position on the machine.

From the bale 10 the reenforcing, generally designated at D, passes between straightening rollers 11 under a guide roller 12, to the top of the bed section of concrete denoted B. The machine 8 is adapted to move under its own power, by a motor 10 G, over the rail E, and as it moves in the direction of the arrow, the reenforcing D automatically feeds onto the bed section B of the road, this bed section being first laid.

The machine 8 has a derrick 13 supported 15 on its framework and comprising a mast with the boom 14. By this derrick the loading bucket, which may be a batch box, designated 15, may be removed from the truck or car of an industrial railway and dumped into the hopper 16, from which its contents pass into the mixer 17. The mixer 17 is adapted to feed mixed aggregates into the distributing bucket 18, on the boom 4 of the machine 8, and this bucket 25 18 supplies the aggregates to be laid as the surface or top section C of the road. These surface aggregates are deposited upon the reenforcing D as the latter is fed to the surface of the bed section B of the road.

30 After being laid the bed section B of concrete will be comparatively soft, but will have ample body to carry the reenforcing D as it is laid, and then in continuous process the surface aggregates are deposited on 35 top of the base section B, upon the reenforcing D.

By the machine above described, and practicing the method set forth, it is evident that a complete reinforced road may be 40 laid in a continuous progressive operation, that no manual work is entailed in handling the reenforcing, and that the surface layer or section of the road bed may be laid quickly after the bed section is deposited,

and will unite firmly with the bed section 45 to provide a solid, monolithic, reinforced, road structure.

It will be understood that any suitable power driven feeding rolls such as designated at 20 may be carried by the supporting means for the metal reenforcement whereby to positively pull or unwind the same from the bale or reeled formation thereof.

Having thus described my invention, what 55 I claim as new and desire to secure by Letters Patent is:—

1. In a machine for laying concrete reenforcing, in combination, a wheeled support having wheels adapted to travel upon road forms at opposite sides of a road sub-grade, a carrier for metal reenforcing mounted upon said support, a series of straightening and feeding rollers adjacent to said carrier and carried by said support for receiving 60 and straightening the reenforcing as it passes over the roll to the sub-grade, a guide roll carried by said support for directing the reenforcing properly to its position on the sub-grade, a power plant upon the support, driving connections between the power plant and feeding rollers, and driving connections between the power plant and wheels of the support, substantially as described.

2. In a machine for laying concrete reenforcing, in combination a wheeled support having wheels adapted to travel upon road forms at opposite sides of a road sub-grade, a carrier for a supply of metal reenforcing carried by said support, a power plant on 70 said support, means for dispensing the reenforcing supported by the carrier operated by said power plant, and means for advancing the portable support, comprising driving mechanism for its wheels operated 75 from the power plant.

In testimony whereof I affix my signature.
JOHN F. ROBB.
